UNITED STATES PATENT OFFICE

2,454,096

MEANS FOR DISCHARGING ROCKETS

Conrad David Schermuly, Alfred James Schermuly, and Charles Schermuly, Parkgate, Newdigate, England, assignors to The Schermuly Pistol Rocket Apparatus Limited, Parkgate, Newdigate, England, a British company

Application July 22, 1944, Serial No. 546,162
In Great Britain May 11, 1943

3 Claims. (Cl. 102—7)

1

This invention relates to means for discharging rockets and has for its object to provide means whereby the rocket may be fired from the sea automatically at a predetermined time.

According to this invention a rocket-discharging device comprises an inner casing, a buoyancy chamber on said inner casing, an outer casing at least partly surrounding said inner casing, a rocket in said inner casing, means for ejecting said inner casing from said outer casing, and means for ejecting said rocket from said inner casing and for igniting the rocket.

The outer casing may completely surround the inner casing, in which case it is formed of two detachable parts, or it may surround only the lower part of the inner casing, in which case it may be detachably secured to the inner casing or its buoyancy chamber. The device according to the present invention is eminently suitable for use from aircraft. For example, if it is desired to illuminate an area of the sea, a device according to this invention, containing a rocket carrying an illuminating flare, may be dropped from the aircraft into the sea whence the rocket is fired into the air.

The invention will now be described with reference to the accompanying drawings, given by way of example, in which Figure 1 is a view, partly in section, of a form of rocket-discharging device in which the outer casing completely surrounds the inner casing, and Figure 2 is a similar view of a modification in which the outer casing surrounds only the lower part of the inner casing.

Referring to Figure 1, the outer casing consists of a lower portion 1 and a cap 2. The lower portion 1 is provided with an igniter 5 of the kind which operates after a delay. Igniters of this kind are known to the art. A wooden plug 8 is located in the outer casing at the bottom thereof, so that a burster 4 contained in the plug 8 is in a position to be fired by the igniter 5. The plug 8 has a recess for the reception of the end of an inner casing 3. A delay fuze 11 and a burster 12 are located in the lower end of the inner casing 3 in such position that the delay fuze 11 can be ignited by the flash of the burster 4. A rocket 7 is located in the inner casing 3 with its rear end resting on the perforated plate 14a adjacent the burster 12. The rocket 7 has a head 7a which may contain a flare, if desired with an attached parachute. The rocket 7 is held in position by spacers 9. A buoyancy chamber 6 is provided on the inner casing 3. The cap 2 is secured to the lower portion 1 of the outer casing by a waterproof seal 10. To ensure that the device will remain in the correct upright position, weights 13, for example of lead, are provided.

In operation, the delay igniter 5 is armed and the device dropped from an aircraft into the sea. The delay of the igniter 5 allows time for the

2

device to assume an upright position in the water before the burster 4 explodes. The explosion of the burster 4 ignites the delay fuze 11 and forces the block 8 from its position in the outer casing, separating the outer casing into its two parts and ejecting the inner casing 3 from the outer casing. This allows the inner casing 3 to rise to the surface by virtue of the buoyancy chamber 6. When the burster 12 explodes, it ignites the rocket 7 and at the same time forces the rocket upwardly, forcing out the spacers 9 thus releasing the rocket for discharge from the inner casing 3.

Referring to Fig. 2 of the drawings, the outer casing 1 surrounds only the lower part of the inner casing 3. The casing 1 is provided with an igniter 5. A plug 8a rests at the bottom of the outer casing and is secured to the inner casing 3. A burster 4 contained in the plug 8a is placed so that it can be fired by the igniter 5. A delay fuze 11 and a burster 12 are located within the plug 8a in such position that the delay fuze 11 can be ignited by the flash of the burster 4. A rocket 7 is located in the inner casing 3 with its rear end resting on a plate 14a, the said rear end of the rocket being adjacent the burster 12. The rocket 7 has a head 7a which may contain a flare, if desired with an attached parachute. A buoyancy chamber 6 is provided on the inner casing 3. The outer casing 1 is secured by a waterproof seal 10 to the buoyancy chamber 6. To ensure that the device will remain stable during its flight through the air, an iron ring 13 is provided. This ring falls off as soon as the case 1 is separated from the buoyancy chamber.

In operation, the igniter 5 is actuated when the device strikes the sea and this ignites the burster 4. The explosion of the burster 4 ignites the delay fuze 11 and separates the outer casing 1 from the buoyancy chamber 6 which then rises to the surface by virtue of its buoyancy. When the burster 12 explodes, it ignites the rocket 7 and forces the plate 14a upwards thus driving the rocket forward and at the same time forces off the cover 14 and allows the rocket to leave the inner casing 3 under its own power.

We claim:

1. A device adapted to be dropped from aircraft into water and to discharge a rocket when in the water, comprising an inner casing, a buoyancy chamber on said inner casing, a rocket in said inner casing, an outer casing surrounding at least the lower part of said inner casing and buoyancy chamber, an igniter on said outer casing adapted to be operated after the device strikes the water, a burster arranged to be ignited by said igniter, a delay fuze arranged to be ignited by said burster, a second burster arranged to be ignited by said delay fuze, whereby upon explosion of said first-mentioned burster, said inner casing is ejected from said outer casing and upon

explosion of said second burster said rocket is ejected from said inner casing and simultaneously ignited.

2. A device as claimed in claim 1 wherein said outer casing is in two detachable parts which completely surround said inner casing and buoyancy chamber.

3. A device as claimed in claim 1 wherein said outer casing surrounds only the lower part of said inner casing and buoyancy chamber and is detachably secured to said buoyancy chamber.
